UNITED STATES PATENT OFFICE.

FRED C. EVANS, OF ITHACA, NEW YORK.

CHARGE-MIXING DEVICE.

1,298,315.

Specification of Letters Patent. Patented Mar. 25, 1919.

Application filed April 19, 1918. Serial No. 229,643.

To all whom it may concern:

Be it known that I, FRED C. EVANS, citizen of the United States, residing at Ithaca, in the county of Tompkins and State of New York, have invented certain new and useful Improvements in Charge-Mixing Devices for Internal-Combustion Engines; and I do hereby declare the following to be a full, clear, and exact description of the invention, such 10 as will enable others skilled in the art to which it appertains to make and use the same.

This invention relates to carbureting devices, and more particularly to a simple, practicable, inexpensive device adapted to be 15 readily connected to or located in the intake flue between the carburetor and the cylinders of an internal combustion engine.

It is one of the objects of the present invention to secure a more thorough mixture of 20 the carbureted air passing from the carburetor through the intake manifold into the cylinders of the motor so as to secure a more thorough and rapid ignition and combustion of the charges of combustible fuel in cylinders.

With these and other objects in view as 25 will be manifest to those versed in the art, the invention consists of the construction, the combination, and in details and arrangements of the parts and features of the invention 30 as will be described in the following specification relative to an embodiment of the invention shown in the accompanying drawings, in which

35 Figure 1 is a side elevation of an ordinary four-cylinder internal combustion engine to which the mixing device is applied in the connection between the carburetor and the manifold, the intake tube being broken away 40 to show the device.

Fig. 2 is a side elevation of the mixer detached from the engine.

Fig. 3 is a transverse section on line 3—3 of Fig. 2 looking in the direction of the 45 arrow.

Fig. 4 is a plan or rectilinear projection of the mixer to more clearly show the staggered relation of the baffle prongs at opposite ends of the device.

50 The invention, obviously, is capable of being designed, proportioned, and constructed for ready adaptation to various types of fuel supply connections for internal combustion engines, in the present instance, such an 55 engine being indicated as at 2, having a manifold 3 connected by an intake connection or

pipe 4 by flanges 5—6 to the outlet 7 of a carburetor 8 which may be, obviously, of any design.

The present invention in its illustrated 60 form is shown as comprising a frame 10, here in the form of a hollow cylinder, of suitable length and of a diameter approximately fitting the interior diameter of the intake pipe or connection 4. While the cylinder 10 65 may be frictionally held if desired *in situ* in the intake connection, preferably, suitable means are provided to enable the positive positioning and holding of the device in an adjusted position in the intake 4, these means 70 being illustrated in the present instance as short, outwardly directed tongues 11, any suitable number of which may be bent up from or attached to the cylinder in any convenient or desired location, these retaining 75 lugs or tongues in the present instance being adapted for location between the connecting flanges 5—6 which join the neck of the carburetor 8 to the lower end of the intake tube 4. One of the important features of the pres- 80 ent invention resides in the means whereby the fuel passing through the intake connec- 85 tions between the carburetor and the manifold is quickly and thoroughly intermixed so as to break up stratum, and to positively produce an intermixture of the minute vapor- 90 ous particles with the air, and thus form a more perfectly carbureted charge for com- 95 bustion in the cylinders of the engine. Therefore, the mixing device includes at one or both ends a series of fingers or baffle mem- 95 bers indicated at 12, secured to or formed integrally with the body of the cylinder 10. These fingers or baffles are shown as tapering lengthwise to a point, and are relatively spaced from each other at their bases to form gaps or passageways 13, which gaps are about equal in width to the width of the bases of the triangular or tapering baffles 12, thus affording a ready path for the flow of 100 the carbureted air through the mixer. The fingers or baffles are in each series bent toward each other in the form of a cone with their tips in close proximity, as clearly shown in Figs. 2 and 3, the baffles preferably being 105 of thin material and therefore flexible, with the result that they will yield under the pressure of the flowing carbureted air so as not materially to retard the flow of the mixture to the cylinders of the engine, and at the 110 same time effectually cause the thorough intermixture of the fuel passing through.

Preferably the series of fingers or baffles at one end of the cylinder 10 are set in staggered relation as to those at the opposite end, this being clearly indicated in Figs. 2 and 4, 5 where the base or connection of one baffle is shown as longitudinally opposite the space between adjacent fingers of the other series.

While the device may be made in many forms, and while the parts may be variously 10 designed, proportioned, and arranged, an inexpensive form of mixer may be secured by producing a blank such as shown in Fig. 4 with the series of baffles 12 at each longitudinal edge, the baffles offset with relation to 15 each other in the above series, and this form of manufacturing device also enables the ready provision of the retaining tongues 11. The blank, obviously, may be rolled into cylindrical form and its overlapping edges 20 10' suitably secured together, and then the series of tongues at each end of the cylinder may be bent convergently, one series projecting upwardly from the end of the cylinder, while the series at the lower end is 25 bent into the cylinder, so that the conically arranged series each converge in the same direction. The retaining lugs 11 are bent to stand perpendicularly to the axis of the cylinder 10, and, therefore, when the mixer is 30 inserted between the connecting flanges 5—6 of the intake connection, the device is se-

curely held in position without any extraneous fastening means.

What I claim is:

1. A mixing device for attachment to intake means of internal combustion engines, comprising a ring with axially spaced series of convergently bent fingers laterally separated to form narrow spaces, the fingers of one series being staggered as to those of the other. 35

2. A mixing device for attachment to intake means of internal combustion engines, comprising a cylindrical tube having inwardly turned tapering prongs at its upper end, the 45 prongs substantially forming a truncated cone, and the prongs being laterally spaced from each other at their junctions with the ends of the cylinder, and a set of inwardly tapered prongs directed upwardly into the 50 cylinder and of a length approximately equaling the length of the cylinder, the prongs at the lower end thereof being spaced from each other at their junctions with the cylinder, and outwardly turned fastening 55 lugs between certain of the prongs at the lower end of the cylinder the prongs of one series being staggered as to those of the other.

In testimony whereof I affix my signature. 60

FRED C. EVANS.
